UNITED STATES PATENT OFFICE.

GEORGE McCARTER, OF DENVER, COLORADO.

COAL-MINING MACHINE.

1,336,039.

Specification of Letters Patent. Patented Apr. 6, 1920.

Application filed December 2, 1918. Serial No. 265,027.

To all whom it may concern:

Be it known that I, GEORGE McCARTER, a citizen of the United States, residing at Denver, in the county of Denver and State 5 of Colorado, have invented certain new and useful Improvements in Coal-Mining Machines, of which the following is a specification.

This invention relates to mining machines 10 and more particularly to that class of machines especially designed for mining coal and known as short wall machines.

Short wall mining machines, as at present constructed and employed in room and pillar mining, are provided with single cutters of the endless or chain type which cut into the working face of the coal near the floor line of the mine and form a horizontal channel or kerf which undermines 15 the coal face so that the body of coal above said channel may be broken down and removed by blasting. When a single cutter machine is used the channel or kerf formed in the working face of the coal is necessarily 20 narrow with the result that the body of coal above said channel, after being blasted, has only a short distance to drop or fall and the dislodged mass of coal often wedges or locks so as to render it necessary 25 for the miner to manually remove the same. The removal of this locked or wedged mass of coal not only necessitates additional labor on the part of the miner but, owing to the 30 fact that the coal must be broken up with 35 a pick or other tool to dislodge the same, often results in an undesirable product known as slack coal.

In order to overcome these objections, I have devised a short wall mining machine 40 having a pair of endless cutters so arranged that when they enter the working face of the coal, spaced longitudinal channels or kerfs are produced defining an intermediate stratum of coal which latter may be readily 45 removed by the miner so as to form an opening or sump extending the entire length of the working face and of sufficient height to produce enough drop or fall for the body of coal above said sump when "shot" or 50 blasted, to prevent locking or wedging and at the same time cause the body of dislodged coal to be broken into relatively large lumps and thrown or spread laterally beyond the working face and in position to 55 be conveniently removed by the miner. Owing to the fact that the body of coal above

the sump when blasted is thrown or spread laterally beyond the working face, the collection of gaseous fumes at the rear of the sump is prevented and the entire mass of 60 coal rendered readily accessible, thereby reducing to a minimum liability of fire in the mine due to the ignition of said fumes.

The primary object of the invention, therefore, is to provide a double cutter short 65 wall mining machine of simple, durable and compact construction which will cut or mine coal sufficiently high on the working face to permit ready dislodgement of the upper stratum of coal with a minimum amount of 70 slack and, consequently, enable the coal to be mined more expeditiously and with less labor, expense and danger of fire than heretofore.

The invention further aims to provide a 75 self-regulating machine capable of cutting either to the right or to the left by merely reversing the position of the picks or cutters and readjusting the propelling cable.

The invention further contemplates the 80 provision of a mining machine including oppositely disposed thread bars having pulleys adjustably mounted thereon and over which extends a propelling cable leading to suitable winding drums on the rear of the 85 machine so that by adjusting the pulleys on the threaded bars the machine may be used for cutting either straight or curved working faces.

A further object is to provide a truck for 90 transporting the machine from one room of the mine to another and means operable by the motive power of the machine for propelling the truck, said motive power also serving to unload the machine from the 95 truck.

A further object is to provide a novel 100 form of belt or conveyer adapted to receive the coal cuttings and discharge them at the rear of the machine.

A still further object of the invention is generally to improve this class of machines so as to increase their utility, durability and efficiency.

Other and incidental objects will appear 105 as the description proceeds. In the drawings wherein I have illustrated the preferred embodiment of the invention, and wherein similar reference characters designate corresponding parts throughout the 110 several views:

Figure 1 is a top plan view of a short

wall mining machine constructed in accordance with the present invention, showing the machine feeding to the left to form a lateral cut in the working face;

5 Fig. 2 is a vertical sectional view, taken on the line 2—2 of Fig. 1;

Fig. 3 is a rear elevation;

Fig. 4 is a top plan view showing in full lines the machine after it has been removed 10 from the truck and resting on the pan, ready to make the longitudinal cut or sump, said figure showing in dotted lines the position of the parts as the cutters enter the working face;

15 Fig. 5 is a top plan view with the pan removed and showing the propelling cable reversed in order to make a right hand lateral cut;

Fig. 6 is a longitudinal sectional view 20 showing the machine in position on the truck employed for transporting said machine from one room to another;

Fig. 7 is a top plan view of the truck, the machine being shown in dotted lines 25 thereon;

Fig. 8 is a top plan view of the supporting pan, the machine being shown in dotted lines on the pan and just prior to its removal therefrom;

30 Fig. 9 is a detail longitudinal sectional view showing the construction of one of the swivel pulley supporting sleeves of the thread bars;

Fig. 9^a is a detail transverse sectional view 35 showing the manner of clamping the split sleeve carrying the sheave supporting arm against swinging movement.

Figs. 10 to 12 inclusive are diagrammatical views showing the method of mining the 40 coal, Fig. 10 showing a transverse sectional view of the working face with the spaced channel or kerfs formed by the cutters, Fig. 11, the sump or longitudinal opening in the coal face formed by removing the stratum 45 of coal between the upper and lower channels, and Fig. 12, the position assumed by the coal when the body of coal above the sump is blasted.

Corresponding and like parts are referred 50 to in the following description and indicated in all the views of the drawings by the same reference characters.

The improved machine forming the subject-matter of the present invention comprises a supporting base 5 having a casing 6 bolted or otherwise rigidly secured thereto. Projecting longitudinally from the forward end of the casing 6 are vertically spaced cutter bars 7, each provided with a 55 pair of sprocket wheels 8 and 8' over which is trained an endless or chain cutter 9. The endless chains 9 are provided with spaced sockets 10 in which are seated reversible teeth or cutters 11 of any desired construction, said cutters being retained within the

sockets by means of set screws 13 so that by loosening the set screws 13 the cutters may be readily removed from the sockets and reversed and thus adapt the machine for cutting either to the right or to the left as 70 will be more fully explained hereinafter. Each cutter bar is provided with a suitable tension device for regulating the tension of the adjacent chain 9, a conventional form of tension device being indicated at 14 in 75 Fig. 1 of the drawings. It will, of course, be understood that one of the tension devices 14 will be employed for each cutter. As before stated, the machine is provided with a pair of cutters arranged in spaced 80 vertical relation so that when they enter the working face of the coal longitudinal kerfs or channels 15 are produced.

Arranged at the front of the casing is a vertically disposed shaft 16 to which the 85 sprocket wheels 8' are keyed or otherwise rigidly secured so as to rotate therewith and mounted on the upper end of said shaft is a beveled gear 17 which meshes with a correspondingly beveled pinion 18 carried by a sliding sleeve 19, the latter being slidably mounted on the power or driving shaft 20 of a gas engine or other suitable motor, indicated at 21. The motor 21 is housed within a suitable hood 22 and when a gas 90 engine is employed as the motive power, a suitable radiator 23 will be arranged at one end of the hood and a fuel tank 24 at the other for supplying fuel to the engine. Arranged at the rear of the machine are a plurality of vertically disposed drums 26 and 27, preferably three in number and around which is wrapped a propelling cable 28 for the purpose of feeding the machine forwardly to produce a longitudinal cut or 95 sump in the working face of the coal and laterally to produce a side cut. The drums 26 and 27 are keyed or otherwise secured to vertical shafts 28 and 29, the lower ends of which project within the casing 6 while the upper ends thereof are provided with beveled pinions 30 which mesh with corresponding pinions 31 on a horizontal shaft 32 so that said drums will rotate in unison. The lower end of the shaft 29 of the central 100 drum 26 is journaled in a bracket 33 arranged within the casing and secured to said shaft above the bracket 33 is a worm gear 34 which meshes with a worm 35 on a longitudinal shaft 36 also arranged within 105 the casing, as best shown in Fig. 2 of the drawings. Slidably mounted on the forward end of the longitudinal shaft 36 is a sleeve 37 having spaced pinions 38 and 39 secured thereto, the forward end of the 110 shaft 36 and the sleeve 37 carried thereby being journaled in a bracket 40. The bracket 40 is secured to the front wall of the casing 6 and is provided with an opening 115 adapted to receive the lower end of the 120

125 130

vertical shaft 16. Keyed or otherwise secured to the vertical shaft 16 is a beveled gear 42 adapted to mesh with the pinion 39 so that when the pinion 18 is moved into 5 mesh with the gear 17 motion will be transmitted from the line shaft 20 of the motor 21 through the medium of the vertical shaft 16 to the pinion 39 and inasmuch as the sleeve 37 carrying the pinion 39 is keyed to 10 the shaft 36, motion will be transmitted through said shaft 36 and worm 35 to the central drum 26 and thence through the medium of the horizontal shaft 32 and pinions 30 and 31 to the drums 27 for the purpose 15 of regulating the draft of the propelling cable 28.

The opposite side walls of the casing 6 are bent or deflected inwardly at 43 to form recesses or pockets in which are journaled 20 longitudinally disposed rollers 44 which bear against the floor of the mine when the machine is traveling either to the right or to the left of the sump.

It will, of course, be understood that 25 when the floor of the mine is soft or soggy suitable metal strips may be placed thereon so as to prevent the machine from sinking into the ground and in which event the rollers 44 will bear against said metal strips 30 instead of engaging the ground directly.

Extending longitudinally of the casing 6 at the rear of the cutters 9 are spaced conveyer belts 45, which receive the coal cuttings from the channels 15 and discharge 35 said coal cuttings through an opening 46 at the rear of the casing. The belts 45 are trained about front and rear transverse shafts 47, the rear shaft 47 being provided with oppositely disposed pinions 48 adapted 40 to mesh with corresponding pinions 49 mounted on the vertical shafts 28 of the end drums. The beveled pinions 49 are keyed to the vertical shafts 28 but are free to slide thereon, each beveled pinion 49 being provided with 45 a yoke and an operating lever 50 by means of which said beveled pinion may be thrown into and out of gear with the adjacent beveled pinion 48 according to whether the machine is traveling to the left or to the 50 right.

Arranged on one side of the machine is a guard or scoop 51 having its outer edge tapered in the direction of the cutters and its rear end provided with an upstanding 55 plate 52 to prevent the coal cuttings from being thrown laterally at the rear of the machine and direct said coal cuttings on to the conveyer belts 45.

In mining machines as at present constructed the coal cuttings from the sump are 60 deposited on the mine floor in the path or movement of the machine and this necessitates the employment of one or more miners to shovel or otherwise remove the coal to permit the passage of the machine. In order to 65

dispense with the additional time and labor in removing the coal cuttings and also to insure a clean path for the passage of the machine in making a lateral cut, I have provided the guard or scoop 51 which, as before stated, receives the coal cuttings and directs them on to the belts 45 for discharge at the rear end of the machine. The guard 51 is bolted or otherwise detachably secured to the side of the casing 6 so that said guard 70 may be readily reversed and placed on either side of the machine according to the direction of travel of the machine in making the lateral cut in the working face.

Arranged on opposite sides of the casing 80 6 and preferably near the top thereof are longitudinally disposed thread bars 53 having their opposite ends rigidly secured in suitable anchoring brackets 54. Threaded on each bar 53 is a nut 55 having a reduced 85 terminal flange 56 which fits in a correspondingly shaped groove 57 formed in a split sleeve 58 so as to form a swivel joint between the same, as best shown in Figs. 9 and 9^a of the drawings. Secured to or formed integral 90 with the sleeves 58 are upstanding brackets or arms 59 on the upper ends of which are journaled sheaves or pulleys 60 for the reception of the propelling cable 28. Suitable screws 59' are threaded in openings in the 95 mating sections of the split sleeves for the purpose of clamping said sections to the nuts 55 and thus preventing swinging movement of the arms 59 after said arms have been adjusted longitudinally of the thread bars. It 100 will, of course, be understood that there is sufficient friction between the interengaging threads on the nuts 55 and thread bars 53 to prevent accidental turning of the nuts on said thread bars, but if found desirable or 105 necessary suitable jamb nuts 55' may be employed for locking the nuts 55 against rotation after adjustment.

By forming the bracket-carrying sleeves and nuts 55 in this manner said parts may 110 be adjusted longitudinally of the machine so as to permit said machine to cut laterally either to the right or to the left. The adjustment of the roller-carrying sleeves 58 on the thread bars 53 also adapts the machine 115 for cutting either straight or curved working faces, as it is obvious that by moving the roller-carrying sleeve on one side of the machine in one direction and the roller-carrying sleeve on the opposite side of the machine in another direction, the entire machine and particularly the cutters thereof 120 may be canted at any desired angle. By reversing the position of the rollers on the thread bars, the machine may also be adapted 125 for cutting either to the right or to the left as will be more fully explained hereinafter. The nuts 55 are preferably provided with exterior angular faces 61 so as to permit said nuts to be conveniently grasped 130

with a wrench or other tool for the purpose of adjusting the nuts and roller-carrying sleeves longitudinally of the thread bars.

For the purpose of transporting the machine from one room of the mine to another, I employ a truck of the construction shown in Figs. 6 and 7 of the drawings. Said truck comprises a bed plate 62 having wheels 63 journaled thereon and adapted to travel on a suitable track 64. The rear axle 65 of the truck is provided with a beveled gear 66 and pivotally mounted on said axle on opposite sides of the gear 66 is a yoke 67 in which is journaled a diagonal shaft 68 carrying oppositely disposed pinions 69 and 70. Slidably mounted on the shaft 68 is a sleeve 71 having a forked arm 72 to which is connected an operating lever 73, the latter being pivotally mounted at 74 so that by tilting the lever 73 the pinion 70 may be moved into and out of engagement with a pinion 75. The pinion 70 normally projects through an opening 74' formed in the bed plate of the truck for engagement with the pinion 75 which latter is carried by a vertical shaft 76 arranged within the casing 6. The pinion 75 is secured to a sleeve 77 which is keyed to the vertical shaft 76, the upper end of said sleeve being provided with a pinion 78 adapted to mesh with the pinion 38 on the sliding sleeve 37, as best shown in Fig. 2 of the drawings. An operating lever 79 is connected with the sliding sleeve 37 so that by moving said lever in one direction the pinion 39 will be caused to mesh with the beveled gear 42 and throw the pinion 38 out of mesh with the pinion 78 and when moved in the opposite direction the pinion 38 will mesh with the pinion 78 and the pinion 39 will be disengaged from the gear 42.

The sleeve 19 is provided with a beveled pinion 80 adapted to mesh with a beveled gear 81 on the upper end of the vertical shaft 76, there being an operating lever 82 connected with the sliding sleeve 19 for the purpose of moving the pinion 80 into and out of engagement with the beveled gear 81.

It will thus be seen that when the gear 39 is in mesh with the beveled gear 42 and the lever 82 is moved so as to cause the pinion 80 to engage the beveled gear 81, motion will be transmitted from the line shaft of the motor 21 through the vertical shaft 76 and pinions 75 and 70 to the truck for the purpose of propelling the machine from one room to the other without affecting the cutters or drums at the rear end of the machine. It will also be seen that when the pinion 39 is moved out of engagement with the beveled gear 42 and the pinion 38 into engagement with the pinion 78 motion will be transmitted from the motor through the vertical shaft 76, pinion 38 and longitudinal shaft 36 to the drums 26 and 27 to wind the propelling cable thereon for the purpose of

unloading the machine from the truck without affecting the cutters. However, when the lever 82 is operated to move the pinion 18 in engagement with the beveled gear 17 and the pinion 39 is moved into engagement 70 with the beveled gear 42, motion will be transmitted from the line shaft of the motor to the sprocket wheels to rotate the cutters and at the same time motion will be transmitted through the gears 42 and 39 to the 75 drums so as to cause the cutters to operate and at the same time feed the machine either longitudinally for sumping or laterally for producing a horizontal cut or channel in the coal face. 80

The method of mining the coal is shown diagrammatically in Figs. 10 to 12 inclusive of the drawings, and by reference thereto it will be seen that the spaced endless cutters form longitudinal channels or kerfs 15 in 85 the working face and between which is an intermediate stratum of coal, indicated at 83, which latter may be readily removed by the miner so as to form an opening or sump 84 extending the entire length of the work- 90 face and of sufficient height to produce enough drop or fall for the body of coal 85 above said sump when "shot" or blasted to prevent locking or wedging and at the same time cause the body of dislodged coal 95 to be broken into relatively large lumps and thrown or spread laterally beyond the working face and in convenient position to be removed by the miner, as best shown in Fig. 12 of the drawings. Owing to the fact that 100 the body of coal above the sump, when blasted at the point 86, is thrown or spread laterally beyond the working face, as shown in Fig. 12, the collection of gaseous fumes at the rear of the sump is prevented and the 105 entire mass of coal rendered readily accessible, thereby reducing liability of fire in the mine, due to ignition of said fumes, to a minimum. Should the gaseous fumes for any reason accidentally collect and ignite, 110 the entire mass of coal as well as the interior of the sump is accessible to the miner for the purpose of extinguishing the fire.

In order to remove the exhaust from the motor there is provided a hose 87, one end of 115 which is connected to the muffler of the engine and at the other end thereof extended to an air passage so that the exhaust from the engine will not contaminate the air within the mine. 120

In connection with the machine, I use an auxiliary frame or pan, indicated at 88, and on which the machine is supported when transporting it on the truck from one room to another and in making the initial 125 longitudinal cut or sump. This pan is indicated in Fig. 8 of the drawings and comprises an openwork structure having brackets 89 extending laterally from the four corners thereof and provided with terminal 130

guides or pulleys 90 over which extend the propelling cable 28. I also employ in connection with the machine suitable rib hooks 91 to which the ends of the propelling cable 5 are anchored during the different movements of the machine in a manner now to be described.

In operation the machine together with the pan 88 is placed on the bed plate 62 of 10 the truck and the lever 82 operated to throw the beveled gear 80 into mesh with the beveled pinion 81 thereby transmitting motion from the motor through the medium of the beveled pinions 75 and 74' to the rear axle 15 of the truck and causing the truck to travel on the track 64 to the place of use. When the truck reaches the working face of the mine the wheels of the truck are anchored in any suitable manner and the lever 73 20 operated to disengage the pinion 70 from the pinion 75. One end of the propelling cable 28 is then anchored to one of the rib hooks 91, as best shown in Fig. 7 of the drawings after which the sleeve 38 is shifted 25 longitudinally of the shaft 36 so as to bring the pinion 38 into mesh with the pinion 78 which transmits motion from the motor through the vertical shaft 76 and longitudinal shaft 36 to the drums, thereby winding 30 the propelling rope on the drums and forcing the machine off of the truck to the position shown in Fig. 4 of the drawings. A rib hook or anchor 92 is then driven into the floor or other portion of the mine and the 35 propelling cable 28 passed around a pulley 93 on said anchoring hook with one end of the cable fastened to one of the pulleys or hooks 90 on the pan. The lever 82 is then shifted so as to move the pinion 18 into engagement with the beveled gear 17 and the 40 sleeve 37 moved longitudinally of the shaft 36 so as to cause the pinion 39 to engage the beveled gear 42 and transmit motion to the drums 26 and 27. With the parts in this 45 position, the propelling cable will move the machine longitudinally on the pan from the position shown in full lines in Fig. 4 of the drawings to the position shown in dotted lines, that is to say, it will cause the cutters 50 to enter or sump into the working face and at the same time slide the machine off the pan and permit the pan to be readily removed. After the machine has been sumped into the working face for a distance of approximately 6 feet, one end of the propelling cable 55 28 is secured to an anchor 94 on one side of the machine and the other end of the propelling cable secured to a rib hook or anchor 95 on the other side of the machine, as best shown in Fig. 1 of the drawings, and in which position the motor through the operation of the mechanism, previously described, will cause the cutters to move laterally and produce the spaced 60 channels or kerfs in the working face previ-

ously referred to. In order to cause the machine to travel in the reverse direction to that shown in Fig. 1 of the drawings, or, in other words, to the right, the position of the pulley-carrying sheaves 28 is reversed by adjusting said sheaves longitudinally of the thread bars to the position shown in Fig. 5 of the drawings and connecting the ends of the propeller cable to the anchors 96, as shown in said figure. After the position of 70 the roller-carrying sleeves has been reversed the position of the cutters or teeth are also reversed in the manner before stated and when the parts are so arranged the machine will cut laterally to the left. After the coal 75 in one room has been cut in this manner the machine is placed on the pan and loaded onto the truck by means of the motor by merely passing the propelling cable over the proper guide pulleys and in which position 80 85 said machine may be conveniently transported on the truck to the next room as will be readily understood.

The machine is self-regulating in character and all operations thereof are performed 90 by the motor by merely adjusting the operating levers and propelling cable as previously set forth.

In this connection it will be noted that the working face of a coal mine in pillar and 95 room mining is generally approximately six feet in height and as the cutters of the present invention each form a kerf approximately three inches in width with an intermediate stratum of coal six inches wide, 100 when said stratum of coal is removed by the miner the sump will be approximately one foot high, thus affording a sufficient drop or fall for the body of the coal above the sump to prevent locking or wedging of the coal 105 incident to blasting which is a very desirable feature as it not only prevents the formation of an undesirable product known as slack coal, but also insures lateral spreading of the coal beyond the working face so that 110 the coal may be readily removed by the miner in less time and with less danger of fire than heretofore.

Having thus described my invention, what 115 is claimed as new is:

1. A mining machine including vertically spaced endless cutters mounted to cut forwardly and laterally in the working face, means operatively connected with the cutters for simultaneously rotating the same, a 120 conveyer arranged at the rear of the cutters, and a scoop arranged on one side of the machine for directing coal to the conveyer when the machine is making a lateral cut.

2. A mining machine including cutting 125 mechanism, means for operating the cutting mechanism to cut forwardly and laterally in the working face, a conveyer adapted to receive the coal cuttings from the cutting mechanism and discharge the same at the 130

rear of the machine, and a scoop arranged on one side of the machine for directing coal to the conveyer when the machine is making a lateral cut.

5. 3. A mining machine including a casing having oppositely disposed openings, vertically spaced endless cutters projecting through the front of the casing, means for simultaneously operating the cutters, an 10 endless conveyer arranged at the rear of the cutters, and a scoop adapted to be attached to either side of the casing at the openings therein for directing coal on to the conveyer when the machine is making a lateral cut.

15. 4. A mining machine including a cutter, means operatively connected with the cutter for actuating the same, thread bars disposed at opposite sides of the machine, drums arranged at the rear of the machine, roller-carrying sleeves engaging the thread bars and adjustable longitudinally thereof, and a propelling cable extending over said drums and the rollers of said sleeves for attachment to an anchor.

20. 5. A mining machine including a supporting frame, vertically spaced endless cutters mounted for rotation on the frame, a motor for actuating the cutters, an endless conveyer mounted at the rear of the cutters, drums mounted for rotation on the frame and operatively connected with the motor, a connection between certain of the drums and the conveyer for rotating said conveyer, thread bars disposed on opposite sides of the frame, sleeves engaging the thread bars and adjustable longitudinally thereof and provided with guides, and a propelling cable extending over the drums and the guides on said sleeves for attachment to suitable anchors.

25. 6. A mining machine including a supporting frame, vertically spaced endless chains mounted for rotation on the frame, reversible cutters carried by the chains, a motor operatively connected with the chains for rotating the same, a conveyer arranged at the rear of the chains and adapted to receive coal cuttings and discharge the same at the rear of the machine, oppositely disposed thread bars carried by the frame, cable guides engaging the thread bars and adjustable longitudinally thereof, drums mounted for rotation on the frame and operatively connected with the motor, and a propelling cable extending around the drums and over 30 the guides for attachment to suitable anchors.

35. 7. A mining machine including a supporting frame, a vertical shaft carried by the frame and provided with spaced sprocket wheels, endless cutters engaging the sprocket wheels, a gear on the upper end of the vertical shaft, a motor, a clutch on the driving shaft of the motor and movable into engagement with the gear of the vertical shaft, a 40 gear secured to the vertical shaft between

the sprocket wheels, a plurality of drums mounted for rotation on the frame and provided with depending shafts, the shaft of one of the drums being provided with a worm wheel, a longitudinal shaft having one end thereof provided with a worm engaging said wheel, and a pinion on the other end of the shaft movable into and out of engagement with the second-mentioned gear on the vertical shaft. 75

8. A mining machine including a supporting frame, a plurality of drums mounted for rotation on the frame and each provided with a depending shaft, a vertical shaft mounted for rotation at the front of the machine, cutting mechanism operatively connected with and rotated by said vertical shaft, a gear wheel secured to the vertical shaft, the depending shaft of one of the drums being provided with a worm wheel, 80 a longitudinal shaft having one end thereof provided with a worm engaging the worm wheel, a pinion mounted on the other end of the longitudinal shaft and movable into engagement with the gear on the vertical shaft, a motor for driving the vertical shaft, an endless conveyer arranged at the rear of the cutters and including a shaft having oppositely disposed pinions, and pinions carried by the vertical shafts of the other drums 85 and movable alternately into and out of engagement with the pinions of the conveyer shaft.

9. A mining machine including a supporting frame, vertically spaced endless cutters mounted for rotation on the supporting frame, a vertical shaft operatively connected with the cutters for rotating the same, a motor for driving the vertical shaft, a gear wheel secured to said vertical shaft, 100 a plurality of drums mounted for rotation on the frame, a longitudinal shaft having one end thereof operatively connected with one of the drums, a sleeve slidably mounted on the other end of the longitudinal shaft 105 and provided with spaced pinions, a second vertical shaft, a pinion carried by the second vertical shaft, and means for shifting the sliding sleeve on the longitudinal shaft to alternately cause the pinions on the 110 sleeves to engage the gear wheel on the first-mentioned vertical shaft and the pinion on the second-mentioned vertical shaft. 115

10. A mining machine including a supporting frame, a vertical shaft mounted for 120 rotation on the frame and provided with spaced sprocket wheels, endless cutters trained about said sprocket wheels, a beveled gear secured to the upper end of the vertical shaft, a motor, a sleeve mounted on the 125 driving shaft of the motor and provided with spaced pinions, one of which is movable into engagement with the gear of the vertical shaft, a second gear secured to the vertical shaft, a plurality of drums mounted for 130

5 tation on the supporting frame and provided with depending shafts, one of which is provided with a worm wheel, a longitudinal shaft having a worm at one end 10 engaging the worm wheel, a sleeve slidably mounted on the other end of the longitudinal shaft and provided with spaced pinions, one of which is movable into engagement with the second gear on the vertical shaft, a second vertical shaft having spaced 15 pinions, one of which is engageable by the adjacent pinion on the sliding sleeve of the motor drive shaft and the other engageable by the adjacent pinion on the sliding sleeve 20 of the longitudinal shaft.

11. A mining machine including a supporting frame, vertically spaced cutters mounted for rotation on the frame and including a driving shaft, a motor operatively 25 connected with the driving shaft of the cutters for actuating the latter, a plurality of drums having their axes of rotation disposed in a vertical plane, a propelling cable extending around said drums, means for transmitting motion from the driving shaft to one of the drums for rotating the same, and means for disconnecting the motion transmitting means from the driving shaft and operatively connecting said means with 30 the motor for rotating the last mentioned drum without affecting the cutting mechanism.

12. A mining machine including a casing, 35 endless cutting mechanism mounted for rotation within the casing and projecting longitudinally beyond one end thereof, a motor for actuating the cutting mechanism, a plurality of drums mounted for rotation on the casing, means for rotating the drums 40 from the cutter operating mechanism, oppositely disposed thread bars secured to the casing, sleeves engaging said thread bars and adjustable longitudinally thereof, up- 45 standing arms carried by the sleeves and provided with terminal rollers, and a propelling cable extending around the drums and over the rollers.

13. A mining machine including a casing, 50 spaced endless cutters mounted for rotation on the casing and including a driving shaft, a motor operatively connected with the driving shaft for rotating the cutters, a plurality of drums mounted on the casing at the rear thereof and each provided with 55 a beveled pinion, a horizontal shaft having beveled pinions engaging the adjacent beveled pinions of the drums for rotating said drums in unison, a connection between one of the drums and the driving shaft of 60 the cutting mechanism for rotating all of

the drums, longitudinal thread bars on opposite sides of the machine, sleeves threaded on said bars and provided with upstanding brackets having guide rollers, and a propelling cable extending around the drums 65 and over said guide rollers.

14. A mining machine including cutting mechanism, means for operating the cutting mechanism, longitudinally disposed thread bars arranged on opposite sides of the machine, rotating drums arranged at the rear of the machine, nuts threaded on the thread bars, sleeves swiveled on the nuts and provided with upstanding arms having guide rollers, a propelling cable extending around 70 the drums and over the rollers, and means for rotating the drums from the cutter operating mechanism.

15. A mining machine including a casing, cutting mechanism carried by the casing, 80 means for operating the cutting mechanism, a plurality of drums arranged at the rear of the casing and operatively connected with and rotated by the cutter operating means, and a conveyer arranged at the rear 85 of the cutting mechanism for discharging coal cuttings through an opening in the rear of the casing.

16. In a coal mining machine, a casing, 90 spaced endless cutters carried by the casing and including a driving shaft, means for rotating the driving shaft of the cutters, terminal and intermediate drums mounted for rotation on the casing and each provided with a depending shaft, means for transmitting motion from the driving shaft of the cutters to the depending shaft of the intermediate drum, a conveyer arranged at the rear of the cutters and having a shaft 95 provided with terminal pinions, pinions carried by the depending shafts of the terminal drums but movable alternately into engagement with the adjacent pinions of the conveyer shaft, and a connection between all 100 of the drums for causing them to rotate in unison.

17. A mining machine including spaced cutters, a motor for operating the cutters, thread bars disposed on opposite sides of the machine, roller-carrying members 110 mounted on and adjustable longitudinally of the thread bars, drums mounted for rotation and operable by said motor, and a propelling cable extending around the drums and over the rollers of said members 115 for feeding the cutters longitudinally or laterally of the working face.

In testimony whereof I affix my signature.

GEORGE McCARTER. [L.S.]
